UNITED STATES PATENT OFFICE

EUGENE F. MARTINET, OF CLEVELAND, OHIO, ASSIGNOR TO THE DUAL SPEEDOMETER COMPANY, OF CLEVELAND, OHIO, A CORPORATION OF OHIO

SPEED-INDICATING DEVICE

Application filed December 22, 1928. Serial No. 327,799.

This invention relates to speed indicating devices, and more particularly speedometers capable of registering certain speeds as desired; and it is among the objects of the invention to provide a construction allowing registration of speed at any given instant with accuracy and convenience. A further object is the mounting of indexing means in a compact and advantageous form. A still further object is the arranging of control means in a relation to simplify attention required. Other objects and advantages will appear as the description proceeds.

To the accomplishment of the foregoing and related ends, the invention, then, consists of the features hereinafter fully described, and particularly pointed out in the claims, the following description and the annexed drawings setting forth in detail certain structure embodying the invention, such being illustrative however of but one of the various ways in which the principle of the invention may be employed.

In said annexed drawings:—

Fig. 1 is a face view of an embodiment of the invention; Fig. 2 is a sectional view taken directly under the cover glass; Fig. 3 is a face view with the entire cover assembly removed; Fig. 4 is an inside or rear view of the cover assembly; Fig. 5 is a side elevation, partly in axial section, of the complete device in operating position; Fig. 6 is a similar view showing the running hand in disengaged position; and Fig. 7 is a sectional view of a detail.

Referring more particularly to the drawings, there is shown a casing 1 of any preferred or usual form and containing therein the translating and odometer mechanism, which may be of centrifugal, magnetic or other type, as preferred, and the detail of which being immaterial to the present invention need not be shown. Extending from the translating mechanism, i. e. the mechanism which converts the rotary motion derived from the vehicle to a proportional speed indicating movement, is a shaft 2 for actuating the indexing means. In the particular form illustrated, the shaft projects slightly through the dial plate 3 which carries an

arcuately arranged scale 4 over which sweeps a running hand 5. This running hand is so mounted as to be moved by the shaft, but when desired can be readily disengaged axially therefrom so as to maintain its position at that instant and thereby show a continuing registration on the corresponding scale reading. The mechanism for accomplishing such control separation from the driving shaft may vary somewhat in its detail, but in the form illustrated involves a hub 6 fixed to the shaft and preferably having an expanded disk-like extension 7. In the hub or rather at a point near the periphery of the disk is a recess, for instance a hole 8, and the running hand 5 carries a coacting projection or pin 9 capable of seating therein. Thus irrespective of any particular detail, the mechanism contemplates generally an inter-engagement between running index or hand and shaft capable of ready separation for registry and ready reengagement in the same operating relation when such registry is no longer required. An advantageous construction involves a grooved collar 10 on the running hand, and a fork 11 engaging in the groove, such that the hand may be carried around by the shaft but without interference from the fork. An arm 11' as an extension from the fork is suitably held at its remote end, as for instance by a fastening to the cover. While this fastening may be in some instances at the side portion of the cover, generally it is preferable to place it, as at 12 in connection with a plate 14 forming a part of the cover assembly. A resilient guard 13 also supported from the cover extends over to a position above the grooved collar 10. Extending through the cover glass 15 is a bushing 16 secured at its inner end to the plate 14 and locked externally by a nut 17, and reciprocably and oscillably mounted in the bushing is a stem 18 which at its inner end is headed at 19 to allow slight oscillatory movement in the arm 11' without separation therefrom. A spring 20 interposed between the arm and the cover normally tends to hold the arm down, the precise position being governed by a thumb lever 21 secured to the outer end of the stem 18 and capable of movement.

100

through a short arcuate sweep, the member 21 in such arcuate sweep travelling over the outer edge of the bushing 16 which in its contour includes a cam depression 22. The thumb lever 21 will thus be seen to allow of tight seating of the running hand in operating engagement with the shaft, as shown in Fig. 5 for instance, when the thumb lever is in the lowest or depressed portion 22 of the cam, and when the thumb lever is turned arcuately so as to ride up on the higher portion of the cam bushing, the stem 18 is correspondingly drawn outwardly and with it the arm 11' to raise the running hand 5 enough to disengage it from driving relation with the shaft.

Mounted also in the cover assembly is a maximum indicating hand 23. Conveniently this may be mounted in plate 14 for the necessary oscillatory movement, a stud 24 headed at 25 suitably providing for such relation, and secured to the hand 23 is a disk 26 frictionally engaged or finely toothed and engaged by a dog 27, the purpose of such arrangement being to maintain the maximum indicating hand in its advanced position at any time, a spring 28 tends normally to return the maximum hand to zero. The maximum hand is driven from the running hand, and for this any suitable interengaging means may be provided; as a projection on one of the ends, for instance a projection 28 on the maximum hand in the normal path of the running hand whereby the maximum hand may be pushed along.

For releasing the maximum hand as held by the dog in its advanced position, a release means is provided, also carried by the cover assembly, and this may include a dog releasing member actuatable through the side of the cover or preferably through the top, and advantageously embodying for instance a wedge member 29 projectable against the dog 27 whereby to crowd it back from contact with the ratchet 26. The actuation of the wedge member 29 may desirably be had by means of a push button 30 on a stem 31 carrying the wedge member 29, the stem being mounted for slight reciprocable movement in a bushing 32 secured to the plate 14 at its inner end and held by a nut 33 against the cover glass externally. A spring 34 serves normally to hold the member 29 out of the path of the dog.

In use, the general mode of operation will be clear from the foregoing. With rotary movement transmitted through connection 35 from the customary flexible lead to the vehicle, and translated by the speedometer mechanism into an oscillatory movement proportionate to the speed, as involved in the movement of shaft 2, the running hand 5 is normally in engagement therewith so as to sweep over the dial and on decline of speed return. When it is desired to retain a regis-

try of the running speed at any given instant, the running hand is disengaged from the shaft at that point so as to remain in its position while the shaft moves irrespective, this being accomplished by throwing the thumb lever 21 arcuately to ride up on the cam raiser, thereby lifting the arm 11' and the hand 5 sufficiently to disengage the connection with the drive. When such registry of that particular point is no longer desired, by reverse throw of the thumb lever 21 into the cam depression, the arm 11' is correspondingly lowered to allow the projection 8 to again seat in the recess 9, and the hand to be carried by the movement of the shaft. By reason of the finger 28 of the maximum hand extending into the path of the running hand 5, the maximum hand, as seen, is pushed along in the excursion of movement of the running hand, and the dog 27 retains the maximum hand. The coil spring 28 tending normally to return the maximum hand to zero is ordinarily overcome by the action of the dog 27. But when it is desired to return such hand, a pressure on the button 30 wedges the dog 27 out of engagement, and the spring 28 thereupon swings the hand back to starting point.

It will thus be seen that a construction is had making possible the obtaining of any desired registry of speed at any particular time, and a separate showing of maximum speed obtained, each being controllable as desired, and the assembly is so mounted as to constitute a self contained unit readily separable from the driving mechanism, thus greatly facilitating repair of the latter. Furthermore, by reason of the positioning of all control means forwardly, the control and operation of the device is greatly facilitated, particularly for the case of traffic officers using motor bicycles and correspondingly requiring a minimum of interference with hand movements in the steering and control of the vehicle.

Other modes of applying the principle of the invention may be employed, change being made as regards the details disclosed, provided the means stated in any of the following claims, or the equivalent of such, be employed.

I therefore particularly point out and distinctly claim as my invention:

1. In a speed indicating device, the combination of a speed indexing member, a shaft adapted to operate said member, and connecting means optionally engageable and disengageable therebetween.

2. In a speed indicating device, the combination of an indexing member, a shaft adapted to operate said member, and a projection on one and a recess in the other optionally engageable and disengageable.

3. In a speed indicating device, the combination of a cover, and a maximum indicating hand carried by said cover.

4. In a speed indicating device, the combination of a cover, and a running hand carried by said cover.
5. In a speed indicating device, the combination of a cover, and a running hand and a maximum indicating hand carried thereby.
6. In a speed indicating device, the combination of a cover, a maximum indicating hand carried by said cover, means for retaining the hand in its advanced position, and means in the cover for releasing the hand.
7. In a speed indicating device, the combination of a cover, a maximum indicating hand carried by said cover, a dog for holding the maximum hand in its advanced position, and a wedge member in the cover for displacing the dog.
8. In a speed indicating device, the combination of a cover, a bushing in said cover, a stem reciprocable in said bushing having a dog-engaging wedge at its inner end, and means normally holding the wedge out of engagement.
9. In a speed indicating device, the combination of a shaft having a free end, a running hand connectible thereto, a plate spaced over said shaft end, another hand mounted in said plate, and interengaging means whereby the running hand may push the other hand.
10. In a speed indicating device, the combination of an indexing member, a shaft adapted to operate said member, a pin on the indexing member, a receiving recess carried by the shaft, and means to optionally separate and engage the pin and recess.
11. In a speed indicating device, the combination of a shaft having a free end, a running hand connectible thereto, a plate spaced over said shaft end, another hand mounted in said plate, ratchet means to maintain said other hand in its advanced position, means extending through said plate to release said hand, and interengaging means whereby the running hand may push the said other hand.
12. In a speed indicating device, the combination of a shaft, a running hand, a projection on said hand, a hub fixed to said shaft and having a recess to receive such projection, and a manually operating member for disengaging said hand.
13. In a speed indicating device, the combination of a shaft having a free end, a hub fastened thereto and having a recess at one point, a running hand having a cooperating projection, another hand mounted coaxial with said running hand and arranged to be pushed thereby, and manually operating means for engaging and disengaging the running hand with said shaft.
14. In a speed indicating device, the combination of a shaft having a free end, a hub disk fixed thereto and having an opening at one point, a running hand having a coacting pin, a plate spaced over said shaft end, a run-
- ning hand mounted in said plate, interengaging means whereby the said hand may push the running hand, and means extending through said plate for separating said running hand from the shaft.
15. In a speed indicating device, the combination of a shaft having a free end, a hub disk fixed thereto and having an opening at one point, a running hand, a coacting pin on the running hand, a grooved hub collar on said running hand having an opening to seat over the end of said shaft, a fork in the groove of said hub collar, and manually operable means for shifting said fork.
16. In a speed indicating device, the combination of a shaft having a free end, a hub disk fixed thereto and having an opening at one point, a running hand, a coacting pin on the running hand, a grooved hub collar on said running hand having an opening to seat over the end of said shaft, a fork in the groove of said hub collar, an arm carrying said fork, a cover plate, an oscillable stud mounted in said cover plate and headed through said fork-arm, and cam means for reciprocating said stud in its oscillatory movements.
17. In a speed indicating device, the combination of a protective glass, a maximum indicating hand carried thereby, means for retaining the maximum hand in its advanced position, means for releasing said maximum hand retaining means, a running hand, a grooved collar on said running hand, a fork supported by said glass and engaging in said grooved collar, a stem extending through said glass to control said fork, and means externally of the glass for operating said stem.
18. In a speed indicating device, the combination of a shaft having a free end, a hub disk fixed thereto and having an opening at one point, a running hand, a coacting pin on the running hand, a grooved hub collar on said running hand having an opening to seat over the end of said shaft, a fork in the groove of said hub collar, a cover plate, an arm support from said cover plate and carrying said fork, a bushing in said cover plate and having a cam depression in its outer hand, an oscillable stem journaled in said bushing and headed through said fork-arm, a spring between said arm and said cover plate, and a thumb lever extending radially from the outer hand of said stem and riding in and out of such cam depression.

Signed by me this 18th day of December, 1928.

EUGENE F. MARTINET.
